UNITED STATES PATENT OFFICE.

CHARLES BURCH NORVELL, OF RICHMOND, VIRGINIA.

AWNING.

Application filed April 18, 1922. Serial No. 554,757.

To all whom it may concern:

Be it known that I, CHARLES B. NORVELL, a citizen of the United States, and a resident of Richmond, in the county of Henrico, 5 and State of Virginia, have made certain new and useful Improvements in Awnings, of which the following is a specification.

This invention relates to an improvement in awnings and has for its object to provide 10 an improved awning wherein means is provided for positively preventing movement of the awning in the wrong direction, thereby precluding the possibility of the awning being torn or otherwise injured.

15 Another object is to provide an improvement of this character which is of simple and durable construction, reliable in operation and easy and comparatively inexpensive to manufacture and install.

20 Other objects and advantages reside in certain novel features of construction, arrangement and combination of parts which will be hereinafter more fully described, and particularly pointed out in the appended 25 claims, reference being had to the accompanying drawing forming a part of this specification and in which:—

Figure 1 is a perspective view illustrating 30 an embodiment of the invention in use upon a building;

Figure 2 is a detailed view in side elevation of the stop or control mechanism;

Figure 3 is a view in front elevation of the mechanism shown in Figure 2;

35 Figure 4 is a detailed view of the mounting of the bevel gear for driving the winding roll, and,

Figure 5 is a detailed view in section on line 5—5 of Figure 2.

40 Referring to the drawings, wherein for the sake of illustration is shown the preferred embodiment of the invention, the numeral 10 designates an awning including, as usual, a swinging frame 11 and a winding 45 roll or shaft 12 upon which the awning is coiled or wound when not in use. The winding shaft or roll 12 is rotatably mounted in suitable bearings provided therefor upon the window frame or building.

50 One end of the winding shaft 12 has fixed thereto a bevel gear 15 which is driven from a bevel pinion 16 secured to the upper end of a short shaft 17, the short shaft being rotatably mounted in a hanger bearing 18 suspended 55 upon the winding roll or shaft 12 and arranged to maintain the bevel pinion 16 and

bevel gear 15 in operative engagement. Pins 19 are carried by the hanger bearing 18 and project inwardly of the bearing and are received in an annular groove 20 formed in 60 the short shaft 17, whereby the short shaft 17 is held against longitudinal movement and free to rotate.

A coupling sleeve 21 connects the lower end of the short shaft 17 to the upper end of 65 a screw 22, by means of bolts 23 and 24, extending through the sleeve and through bolt holes provided in the short shaft 17 and the screw 22 respectively. The lower end of the screw 22 is connected to the upper end of a 70 square shaft 25 by means of a coupling 26 and bolts and nuts 27 and 28. The lower end of the square shaft 25 extends into the gear boxing 29, wherein suitable gears are arranged to actuate the square shaft 25 75 from a crank 30 in the usual manner.

Angle brackets designated at 32 and 33 are secured to the building or window frame and upon these brackets the guide rod 34 is supported by means of channel shaped 80 attaching plates 35 and 36 having threaded engagement with the guide rod, and nuts 37 and 38 threaded upon ends of the guide rod 34 and engaging the brackets. The horizontal arms or portions of the brackets 32 85 and 33 are extended outwardly beyond the connection of these arms with the guide rod and these extensions are provided with openings which receive the short shaft 17 and screw 22 respectively, to prevent horizontal 90 displacement of these parts. Preferably these horizontal arms or portions of brackets are reinforced by plates 39, 40 and 41, which are held from turning by the flanges of the attaching plates 35 and 36. 95

A travelling nut 45 is provided and is formed with a threaded bearing which operatively engages the screw 22. The travelling nut also includes a guide opening through which the guide rod 34 extends, the guide 100 rod being a sliding fit in the guide opening of the travelling nut.

When the crank 30 is turned to raise or lower the awning the motion of the crank is transmitted through the square shaft 25, 105 screw 22, short shaft 17, beveled gears 15 and 16 to the winding shaft or winding roll 12 and the winding roll or shaft winds or unwinds the awning 10 thereon accordingly as the awning is being raised or lowered. 110

It is to be noted, however, that when the screw 22 turns, as it must whenever the awn-

ing is raised or lowered, the motion of the screw 22 will impart a rectilinear motion to the travelling nut 45, since the threaded bearing of the travelling nut is operatively engaged with the screw and the guide opening of the nut is operatively engaged by the guide rod. The arrangement is such that when the awning is raised and completely wound around the roll or shaft 12, the travelling nut will engage the lower end of the sleeve coupling 21, and so preclude the operator from applying any further winding movement to the shaft 12 from the crank 30. Similarly when the awning has been completely lowered that is unwound as far as it is supposed to unwind from the shaft 12 the travelling nut engages the attaching plate 36 and plate 34, to prevent further unwinding movement or further lowering of the awning. In this manner it is impossible for the operator to tear the awning by winding it in the wrong direction and thus applying destructive forces to the awning 10, since when the awning has been completely raised further motion tending to raise the awning will be positively prevented by the action of the travelling nut and sleeve 21, the sleeve for this purpose constituting an abutment and similarly after the awning has been completely lowered further lowering

movement is prevented by the engagement of the travelling nut 45 with the plates 36 and 40 which also constitute an abutment for this purpose.

I claim:

1. In an operating means for awnings, an actuating shaft made up of sections, releasable means for coupling said sections to each other, and means cooperable with one of the sections for limiting the movement of the awning.
2. In an operating means for awnings, an actuating shaft made up of sections, one of said sections comprising a screw, coupling means between said sections, a travelling nut operatively engaged with the screw, one of the couplings constituting an abutment engageable with the travelling nut.
3. In an operating means for awnings, an actuating shaft made up of sections, one of said sections comprising a screw, coupling means between said sections, a travelling nut operatively engaged with the screw, one of the couplings constituting an abutment engageable with the travelling nut, and a guide rod operatively associated with the travelling nut for constraining the same to rectilinear movement.

CHARLES BURCH NORVELL.
